UNITED STATES PATENT OFFICE.

JAMES H. McCAMERON, OF ST. LOUIS, MISSOURI.

VALIDATION-CERTIFICATE.

No. 894,895.

Specification of Letters Patent.

Patented Aug. 4, 1908.

Application filed July 13, 1907. Serial No. 383,683.

To all whom it may concern:

Be it known that I, JAMES H. McCAMERON, a citizen of the United States, residing at the city of St. Louis and State of Missouri, have invented certain new and useful Improvements in Validation-Certificates, of which the following is a specification, reference being had to the accompanying drawings.

10 My invention relates to improvements in tickets and particularly to improvements in tickets or certificates, which when attached to railroad tickets, will extend the limit of, or validate the latter, indicating upon what 15 date or day, and train or trains the railroad ticket will be accepted as good. Thus, certain classes of railroad tickets sold for the benefit of the general public, are sold under contract with the original purchaser, wherein 20 the original purchaser agrees to comply with certain express conditions therein stated and more particularly that the original purchaser, will, prior to a certain day, identify himself to the satisfaction of the terminal, joint or 25 validating agent as the case may be, as the original purchaser of said ticket. This identification may be effected by signature or other means; and as a means of certifying that the passenger has so identified himself 30 in compliance with the terms of his contract, one of these validating certificates is attached to the ticket making it good and valid for return passage and showing the conductor at a glance whether the ticket has 35 been presented for validation according to contract, within the proper time. Other uses of my new validation certificate will be made to appear hereinafter.

In the drawings illustrating the principle 40 of my invention and the best mode now known to me of applying that principle, Figure 1 shows the validation certificate complete; and Fig. 2 shows the same certificate when its margin has been torn off for the purpose hereinafter set forth.

The ticket or paster consists of two main portions; to wit, the certificate portion a and the record or advice portion b. Each of these portions bears an identifying or tally 50 number c by which the two portions may be identified and a record kept after they have been separated from each other. The advice portion is provided at d with blanks for describing the nature of the ticket to which the 55 certificate portion has been pasted, the description including the name of the issuing line e, the form of the ticket validated f, its number g, the place where sold h, the date of sale i, the route over which the passage was taken j, and the name of the purchaser k, and other data. On the certificate portion blanks are left for writing in the name of the issuing line at *e, the form of the ticket validated at *f, its number at *g, and other data and the signature of the original purchaser at *k. The certificate portion also gives the name of the validating agency m, and the name of the place n from which the ticket validated is good for passage.

Common to the advice portion and the certificate portion before the separation of these parts (Fig. 1) are the year o, the month p, the day q and hours of the day (both forenoon and afternoon) r; and these are arranged so that when the advice portion is torn from the certificate portion, the torn or irregular margin of the latter will indicate to the conductor the year, month, day and hour before which the ticket validated must be used in order to entitle the original purchaser to the passage described by said ticket. The torn or irregular margin of the advice portion will indicate the same information and may serve as a record.

The certificate is signed by the validating agent, as at s.

I claim:

1. A paster consisting of two portions and bearing matter indicating that a ticket will be validated by the attachment of the paster thereto, said matter also indicating upon which train the ticket will be good when so validated, and having printed upon it characters indicating days of the month and hours of the day, said characters being arranged in columns, whereby after separation of said portions from each other, a time limit may be read from both portions.

2. A paster of the character described consisting of a certificate portion and a record portion; each of said portions having printed thereon means for describing the ticket to which the paster is designed to be attached and for indicating that the paster is to be attached to said ticket; and said paster having printed upon it characters which indicate a time, said characters being arranged between the said means printed upon the certificate portion and those printed upon the record portion of the paster.

3. A paster of the character described provided with a plurality of characters which are arranged in columns and which indicate days and hours of the days; and having printed upon one side of said columns means which identify the ticket to which said paster is to be attached and for indicating that the paster is to be attached to said ticket.

4. A paster of the character described having printed thereon in columns a plurality of characters for indicating times of departure 10 of trains and upon one side of said columns means for indicating the place of issue of the paster and the place of departure of the trains; said paster bearing matter indicating that it will render valid and good a railroad 15 ticket by its attachment thereto.

5. A paster of the character described having printed thereon a plurality of characters for indicating times of departure of trains and a plurality of characters for describing a railroad ticket; said paster bearing matter 20 indicating that it will render said railroad ticket valid and good for passage upon said trains by its attachment to said ticket.

In witness whereof, I have hereunto set my hand in the presence of two witnesses at 25 said St. Louis, this 20th day of June, 1907.

JAMES H. McCAMERON.
